UNITED STATES PATENT OFFICE

CHARLES PECKERMAN, OF NEW YORK, N. Y.

DESIGN FOR AN ILLUMINATED PORTABLE DISPLAY DEVICE

Application filed September 1, 1931. Serial No. 40,975. Term of patent 14 years.

To all whom it may concern:

Be it known that I, CHARLES PECKERMAN, a citizen of the United States and residing at New York, in the county of New York and State of New York, have invented a new, original, and ornamental Design for an Illuminated Portable Display Device, of which the following is a specification, reference being had to the accompanying drawings, forming part hereof.

Fig. 1 is a perspective view of an illuminated portable display device showing my new design;

Fig. 2 is a top plan view thereof.

I claim:

The ornamental design for an illuminated portable display device substantially as shown.

CHARLES PECKERMAN.
